UNITED STATES PATENT OFFICE

JESSE BERNICE ROUSE, OF DUNN, NORTH CAROLINA

ACCELERATOR HEAT PROTECTOR

Application filed July 28, 1930. Serial No. 471,286.

This invention relates to an accelerator heat protector or what might also be called a rubber cap or cover for a pedal.

The object of my invention is the construction of a novel and efficient ventilated cap for the accelerator pedal of an automobile, such as Model A of the Ford automobile.

Another object of my invention is the construction of a simple and efficient rubber cap or cover for the head of an accelerator, whereby heat is not imparted to the shoe or foot of the operator.

With the foregoing and other objects in view, my invention comprises certain novel constructions, combinations and arrangements of parts as will be hereinafter fully described, illustrated in the accompanying drawings, and more particularly pointed out in the appended claim.

20 In the drawings:

Figure 1 is a perspective view of a device constructed in accordance with the present invention.

Figure 2 is a sectional view taken on line 25 2-2, Figure 1, and looking in the direction of the arrows.

Figure 3 is a sectional view taken on line 3-3, Figure 2, and looking in the direction of the arrows.

30 Referring to the drawings by numerals, 1 is the accelerator head (dotted lines Fig. 2) and 2 is the stem thereof, upon which my device 3 is placed.

The device 3 is preferably formed of rubber 35 and comprises a body 4 having parallel upstanding ribs 5 on its upper face. The body 4 is hollowed out and has on its bottom an inwardly extending annular flange 6. In the sides of the body 4 are a plurality of ventilating openings 7. In the body 4 is a central

40 depending lug 8 and a plurality of depending tits 9, which tits are of the same length as lug 8, so that the lower ends of said tits and lug bear upon the top of the head 1, spacing the upper rib-carrying part of body 4 from the metal accelerator head. This gives room 45 for air to circulate, through ventilating openings 7, over the top of said head, thereby cooling the head and preventing the device 3 from becoming greatly heated, resulting in keeping

the shoe or foot of the operator cool and comfortable. The tits 9 are distributed around the central lug 8 so that pressure upon the ribbed top will be evenly distributed upon the metallic accelerator head 1, thereby increasing the life of the device by having it worn evenly throughout.

55 The device will easily slip over a head 1 and will be securely fastened thereon by flange 6 without any other fastening means.

60 I have found from practical experience with a working model that my ventilated rubber cap is efficient and comparatively inexpensive to manufacture.

65 While I have described the preferred embodiment of my invention and illustrated the same in the accompanying drawings, certain minor changes or alterations may appear to one skilled in the art to which this invention relates, during the extensive manufacture of the same, and I, therefore, reserve the right 70 to make such changes or alterations as shall fall within the scope of the appended claim.

75 What I claim is:

As a new article of manufacture, a pedal cap formed from a single piece of rubber and comprising a body having ribs on its upper face and hollowed out within and with an annularly inwardly extending flange on its bottom, said ribs forming spaces therebetween open at their ends, said body provided in its sides with ventilating openings opening upon the hollow interior of the body, and a central depending lug and depending tits within said hollow body, constituting spacing means, 80 substantially as shown and described.

85 In testimony whereof I hereunto affix my signature.

JESSE BERNICE ROUSE.
